UNITED STATES PATENT OFFICE

JOHN F. MACKAY, OF LANCASTER, PENNSYLVANIA

BROODER

Application filed November 16, 1928. Serial No. 319,760.

This invention relates to brooders intended for artificial mothering of young chicks and the like, and more particularly to brooders of the type wherein a downwardly deflecting hood surrounds a centrally located heater.

The aim of my invention is to provide, in connection with such brooders, for continuous replacement of air beneath the hoods, and at the same time insure, with absolute accuracy and predetermination, maintenance of a uniform temperature in simulation of the naturally induced atmospheric conditions necessary to the propagation of healthy chicks.

How the foregoing and other important advantages can be readily attained in practice will be manifest from the detailed description following of the typical embodiment shown in the drawings, wherein Fig. I is a plan view of my improved brooder with a portion of the hood broken away.

Fig. II is a view showing the brooder partly in elevation and partly in vertical section.

Fig. III is a fragmentary sectional view on a larger scale, taken as indicated by the arrows III-III in Fig. I; and

Fig. IV is a fragmentary view, looking in the direction of the arrows IV-IV in Fig. III.

With more detailed reference to these illustrations, 10 designates a heater stove embodying a fire chamber 11 which is accessible for fueling from the top through a cover protected opening 12, and an underlying ash pit 13 with a closure door 14; said fire chamber and ash pit being set apart by a horizontal grate 15, all more or less after common practice. In adapting the heater stove 10 to the purposes of my invention, I provide it with a draft inlet 16 into the ash pit 13; which inlet is located, in the present instance, diametrically opposite the door 14, and approached through a hollow fitting 17 attached to or forming an integral part of the stove casing. As shown, the fitting 17 affords connection for a vertical draft pipe 18 that extends up substantially to the level of the stove top. I further supplement the heater stove 10 with a tubular draft outlet fitting 19 in registry with the eccentrically-disposed flue orifice

20, said fitting having a check draft opening 21 in its side and affording pivotal bearing for a damper 22 arranged to control air flow through the check draft opening 21. From Fig. III it will be observed that the damper 22 is appropriately shaped for capacity to swing between the limits indicated in full and broken lines, and that its gravity center is so disposed as to predetermine automatic closing. As shown, the flue pipe 23 is telescopically engaged over the top of the fitting 19 so as to form an axial continuation thereof for connection to a chimney.

Supported from the top of the stove 10 is a surrounding downwardly deflecting conical hood 25, such as may be conveniently made from sheet metal and incidentally provided with an orifice 26 to permit protrusion of the vertical draft inlet pipe 18 above said hood. As shown, the draft pipe 18 has a covering 18a of insulatory material to prevent local overheating of the atmosphere beneath the hood.

For the purpose of automatically governing the heater 10 for maintenance of a definite predetermined temperature beneath the hood 25 with attendant circulation of air, I provide means as follows: Riveted or otherwise fastened to the outer face of the hood 25, near its bottom edge, is a bracket piece 27 that is tapped to take an adjusting screw 28 with a winged manipulating head. This screw 28 carries a pivot support 29 for an arm 30 which extends upward along the slope of the hood 25, i. e. in a direction radially of the stove 10 and in line with the flue 18, while its free end lies beneath an actuating projection 31 on the check draft damper 22. Adjacent the pivot support 29, the arm 30 is formed with a circular downwardly-flanged invert cup-like enlargement 31 whereof the top is perforated as at 32. This cup-like enlargement 31 functions after the manner of a cover member incidental to valvular action with an upstanding flange guard 33 of somewhat larger diameter around a number of air exhaust apertures 34 through the hood 25. The cup-like enlargement 31 of the arm 30 and the flange guard 33 moreover jointly constitute a shield for a wafer thermostat 35

100

which is thus subjected directly to the heated air exhausted through the apertures 34 from beneath the hood 25. In the present instance, the thermostat 35 is secured to the arm 30 as a consequence of having its rivet stud headed over as at 36; and on its free bottom face carries a lug 37 that engages an abutment 38 secured to the hood 25 axially within the flange guard 33.

10 The draft of the heater 10 is controlled by a disk 39 which is moved toward and away from the top end of the flue pipe 18 through the medium of a lever 40 having pivotal support on a bearing bracket 41 secured to the hood 25. That end of the lever 40 carrying the disk 39 over-balances the shorter upwardly rounded tail end 42 which is thus urged into contact with the arm 30 for actuation thereby.

15 20 With the described arrangement, it will be seen that increase in the temperature of the exhaust air is attended by expansion of the thermostat 35 and lifting of the arm 30 from the position illustrated in Fig. III. As

25 the action proceeds, the free end of the arm 30 will engage the projection 31 on the check damper 22 and gradually swing the latter to open position; while the lever 40 is concurrently permitted to lower the disk 39 over 30 the open top of the draft pipe 18, thereby reducing the fire in the heater 10. Through incidental elevation of the cupped enlargement 31 of the lever 30, it will also be seen that a greater volume of the heated air is

35 allowed to escape peripherally over the edge of the flange guard 33. Decrease in the temperature of the exhaust air on the other hand will result in converse action of the mechanism, that is to say: the thermostat 35 will contract with attendant lowering of the arm 30, closing of the check draft damper 22, and opening of the draft pipe 18 through lifting of the cover disk 39. At the same time, the cupped enlargement 31 moves telescopically into the flange guard 33 thereby re-

40 stricting peripheral escape of exhaust air around the top edge of said guard, in a manner wholly obvious from Fig. III. Thus by compensative action between the several 45 parts of the organization in the manner described, I am able to insure continuous replacement of foul air while maintaining a uniform temperature beneath the hood 25 as requisite to the successful nursing of chicks, the temperature being predeterminable through adjustment of the wing screw 28, whereby the relation of the arm 30 may be changed with respect to the check damper 22 and the lever 40 controlling draft into the heater 10.

50 Moisture is supplied for humidification of the air beneath the hood 25 through evaporation of water from the pan 45, shown in the present instance as strapped to the draft inlet pipe 18.

Having thus described my invention, I claim:

1. In a brooder, a heater, a surrounding downwardly deflecting hood, and a thermostat in a telescopic shield exterior of the hood subject to the action of heated air exhausted from beneath said hood to automatically actuate an inlet control for fresh air to the heater while concurrently operating a gravity influenced check in the flue outlet therefrom for the purpose of maintaining a uniform temperature under the hood. 70

2. In a brooder, a heater stove, a surrounding downwardly deflecting hood, a draft inlet for the heater open beyond the confines of the hood, and a thermostat in a telescopic shield exterior of the hood with means to automatically control flow of air into the draft inlet of the heater while concurrently actuating a gravity closable damper in the flue outlet therefrom for the purpose of maintaining a uniform temperature under the hood. 75

3. In a brooder, a heater stove, a surrounding downwardly deflecting hood, a draft inlet for the heater open above the hood, and a thermostat in an adjustable telescopic shield having perforate ends and co-ordinate means to automatically govern flow of fresh air into the upper open end of the draft inlet of the heater and simultaneously control a gravity closable damper in the flue outlet therefrom for the purpose of maintaining a uniform temperature under the hood. 80

4. In a brooder, a heater stove, a surrounding downwardly deflecting hood, a draft inlet for the heater open beyond the confines of the hood, and a thermostat housed in a telescopic shield having perforate ends and subject to the action of heated air exhausting through said shield from beneath the hood to automatically govern flow of air into the upper end of the draft inlet aforesaid while concurrently actuating a gravity closable check damper in the flue outlet therefrom for the purpose of maintaining a uniform temperature under the hood. 90

5. In a brooder, a heater stove with a draft and a gravity closable check damper controls, a surrounding downwardly deflecting hood, and a thermostat housed in an adjustable telescopic shield having perforate ends and subject to the action of heated air exhausting through said shield from beneath the hood to automatically govern the aforesaid draft and check damper controls for the purpose of maintaining a uniform temperature under the hood. 100

6. In a brooder, a heater stove, a surrounding downwardly deflecting hood, a draft pipe extending up through the hood from the heater, means to control flow of air into the top of the draft pipe, a gravity closable check draft damper in the flue of the heater above the hood, a thermostat housed in an adjustable telescopic shield exterior to the hood and 105

having perforate ends, and co-ordinate co-active means to concurrently and automatically govern the flow of fresh air into the draft pipe and the check draft damper for the purpose of maintaining a uniform temperature under the hood.

7. In a brooder, a heater stove, a surrounding downwardly deflecting hood, a draft pipe extending up through the hood from the heater stove, means at the top of the draft pipe to control flow of air thereinto, a check draft damper in the flue of the heater above the hood, an arm with a fulcrum support on the outer surface of the hood coordinated with both the draft control means and the check draft damper, and a thermostat subject to the action of heated air exhausted from beneath the hood to actuate the arm aforesaid thereby to automatically govern the heater for the purpose of maintaining a uniform temperature under the hood.

8. In a brooder, a heater, a surrounding downwardly deflecting hood with an aperture permitting exhaust of heated air from beneath, an upstanding guard around the aperture, a cover member adapted for valvular action with the guard, and a thermostat within the cover member subject to the action of the heated air flowing through the aperture to actuate said cover member thereby to automatically govern exhaust from under the hood.

9. In a brooder, a heater stove, a surrounding downwardly deflecting hood, a draft pipe extending up through the hood from the heater stove, means at the top of the draft pipe to control flow of air thereinto, a check draft damper in the flue of the heater above the hood, an arm with fulcrum support on the outer surface of the hood, said arm being coordinated with both the draft control means and the check draft damper aforesaid, an upstanding guard surrounding an aperture through which heated air is permitted to exhaust from beneath the hood, a cover member on the arm aforesaid adapted for valvular action with the guard to control exhaust, and a thermostat within the cover member subject to the action of the heated air flowing through the aperture to actuate the arm thereby to concurrently control the heater and the exhaust for the purpose of automatically governing air circulation with maintenance of a uniform temperature under the hood.

10. In a brooder, a heater with controls, a surrounding downwardly deflecting hood with a perforate area therein permitting exhaust of heated air from beneath, and means actuated by a thermostat housed in a telescopic shield exterior of and about the perforate area for concurrently governing the heater controls and exhaust through the perforate area thereby to automatically regulate

late air circulation with maintenance of a uniform temperature under the hood.

11. In a brooder, a heater with controls, a surrounding downwardly deflecting hood with a perforate area therein permitting exhaust of heated air from beneath, means actuated by a thermostat housed in a telescopic shield exterior of and about the perforate area for concurrently governing the heater controls and exhaust through the perforate area thereby to automatically regulate air circulation with maintenance of a uniform temperature under the hood, and means whereby the thermostatically actuated means may be adjusted to predetermine the temperature maintained as aforesaid.

In testimony whereof, I have hereunto signed my name at Tullytown, Pennsylvania, this 10th day of November, 1928.
